UNITED STATES PATENT OFFICE.

THEOPHILUS REES MILLISON, OF INDIANAPOLIS, INDIANA.

INTERNAL MOLD FOR BURIAL-VAULTS.

SPECIFICATION forming part of Letters Patent No. 723,477, dated March 24, 1903.

Application filed August 4, 1902. Serial No. 118,629. (No model.)

To all whom it may concern:

Be it known that I, THEOPHILUS REES MILLISON, a citizen of the United States, residing at Indianapolis, in the county of Marion and State of Indiana, have invented certain new and useful Improvements in Internal Molds for Burial-Vaults, of which the following is a specification.

In the construction of burial-vaults it is essential, in order to produce a thoroughly practical, durable, water and burglar proof vault, that there shall be no joints through which water may pass into the interior of the vault.

For this purpose the vault must be so constructed that when completed it will be of a single piece. In a construction of this character care must be taken to prevent all possibility of any expansion of the internal mold during the time when the cement is becoming set or thereafter, as such expansion would result in cracking the walls of the vault.

The object of my invention is, therefore, to produce a mold for the interior of burial-vaults or similar receptacles, which shall be of such character that it may be removed from the vault practically so soon as the walls of the same are formed and before said walls have set, the removal being accomplished without disintegrating the inner surface of the vault.

The accompanying drawings illustrate my invention.

Figure 1 is a plan of a vault in process of construction with my improved mold in the interior thereof. Fig. 2 is a section on line 2 2 of Fig. 1 with the mold removed and showing the manner of producing the top, and Fig. 3 is a perspective view of the mold.

In the production of a mold which is to be removed from the surface of the cement before the cement has set, it is essential that the mold be made in sections having at least one surface dimension comparatively small, so that each section can be individually removed from the surface of the cement by a sliding movement, which will maintain the integrity of the surface from which the mold is withdrawn. My mold is therefore formed by four corner angle-pieces 5, preferably angle-iron, of a length equal to or greater than the internal height of the vault which is to be constructed. These four angle-irons 5 form the

external vertical corners of the mold, and the sides of the mold are then formed by a plurality of slats 6, extending from within one flange of one angle-iron to the adjacent flange of the adjacent angle-iron. Similarly the ends of the mold are composed of a plurality of slats 7, and each of the slats 6 and 7 is provided at each end with an angularly-arranged transverse notch 8, into which the edges of a locking-bar 9 may be introduced. Passing through bar 9 are screws 10, which pass into threaded openings 11 in the angle-irons 5.

In practice my mold will consist of a single set of angle-irons 5 and locking-bars 9 (and the accompanying screws) of a height equal to or slightly greater than the depth of the deepest vault which may be required. The side slats 6 and end slats 7 will then be furnished in several sets of varying lengths, so that a mold of any standard length and width may be obtained, the height or depth being determined by the number of slats which are used.

In operation that set of slats 6 and 7 which most nearly approaches a size into which the desired casket may be introduced is selected and the ends thereof inserted between the flanges of the angle-irons 5 and the locking-bars 9, a sufficient number of slats being used to produce the required height of mold. Screws 10 are then drawn up until each locking-bar rests within the notches 8 and draws the angle-iron closely upon the slats, so as to firmly hold the parts in position. The grave is dug with a width equal to the width of the mold plus twice the thickness desired for the cement walls and a length equal to the length of the mold similarly increased. Prior to the arrival of the casket at the cemetery a floor of cement is laid in the bottom of the grave and my improved mold then placed centrally in position upon this floor, whereupon cement is introduced between the mold and the walls of the grave. Before the cement walls thus formed have entirely hardened the operator loosens the screws 10, removing said screws and the locking-bars 9, whereupon the slats of the sides and ends may be individually slid endwise, so as to loosen from the cement without disintegrating the face, and thus be easily removed in succession. When the slats

composing the sides and ends of the mold have been removed, the screws 10 may be reintroduced to serve as handles to facilitate the removal (preferably by a vertical sliding) 5 of the angle-bars. As soon as the casket arrives it is lowered into the vault thus formed (and from which of course the mold has been withdrawn) and a cover of corrugated sheet metal 12 laid across the top of the vault, the 10 edges thereof projecting slightly upon the walls, as shown. The operator then continues the construction of the vault by spreading a layer of cement over the corrugated metal, said metal serving as a support for the 15 cement until the same hardens. I have found by experience that even though the walls be twenty-four hours old the cement of the top will so firmly unite with the cement of the walls that after all of the parts have firmly 20 set it is impossible to remove the top at the line of union.

I am aware that it has heretofore been proposed to form a burial-vault of substantially unitary walls; but, so far as I am aware, it 25 has been proposed to produce such a vault by the use of a box-like mold, of wood—such, for instance, as the pine box in which caskets are shipped—said boxes or molds being allowed to remain in the completed vault. My 30 experience leads me to the conclusion that in such structures the absolutely unavoidable absorption of water by the mold-box from the cement results in an irresistible expansion of the mold within the vault, such expansion 35 generally taking place a number of hours after the vault has been supposed to have been completed, and such expansion resulting unavoidably in a cracking of the walls of the vault, and thus rendering impossible the accomplishment of the very result for which 40 said vault was produced. I am also aware that hollow cement structures have heretofore been formed by means of molds having movable parts, which enable the withdrawal 45 of the mold from the completed hollow article; but, so far as I am aware, I am the first

to produce a mold which during operation is rigid and which is yet of such character that the sections from which it is made may be given a sliding movement parallel with the 50 cement face to facilitate the withdrawal of the individual sections, at the same time maintaining and perfecting the integrity of the surface from which the mold is withdrawn.

I therefore claim as my invention—

1. A mold for burial-vaults consisting of corner-standards having inner corners free in line of the side slats, sides composed of a plurality of slats of less length than the total 6: length of the mold, and means for detachably clamping said slats to said corner-standards whereby, upon the completion of the walls of the vault, the clamping means may be released and the individual slats composing the 65 side walls may be slid endwise so as to be individually removable from the vault in a manner to maintain the integrity of the surface thereof, while the corners remain in position, and the corner-posts may also be withdrawn from the mold.

2. A mold for burial-vaults consisting of sides composed of a plurality of slats each having a transverse notch in its inner face at each end, vertical corner-angles adapted 75 to lie outside of the side slats and having free inner corners in line with said slats, a locking-bar for each corner-angle adapted to rest in the notches of adjacent ends of two series of slats so as to maintain the ends of 80 the slats at a distance from the inner corner of the corner-angles, and bolts for clamping the corner-angles and locking-bars upon the slats, substantially as and for the purposes set forth.

In witness whereof I have hereunto set my hand and seal, at Indianapolis, Indiana, this 28th day of July, A. D. 1902.

THEOPHILUS REES MILLISON. [L. S.]
